UNITED STATES PATENT OFFICE.

JOHN D. BARBER, OF WEST PARK, OHIO.

SECTIONAL BURIAL-VAULT.

1,393,485.

Specification of Letters Patent. Patented Oct. 11, 1921.

Application filed March 3, 1919. Serial No. 280,297.

To all whom it may concern:

Be it known that JOHN D. BARBER, citizen of the United States, residing at West Park, in the county of Cuyahoga and State of Ohio, has invented certain new and useful Improvements in Sectional Burial Vaults, of which the following is a specification.

My invention relates to a sectional burial vault, and the object of the invention is to 10 provide a burial vault made of reinforced concrete slabs or sections adapted to be easily assembled and then securely united together and hermetically sealed by a cement or grouting poured into specially formed 15 gutters and grooves paralleling the joints. Each slab is reinforced with iron rods extending into the corners where an interlocking effect is obtained, and the cover slab is provided with handles secured to or forming 20 part of the reinforcing rods extending longitudinally thereof.

Figure 1 is a sectional view vertically and longitudinally through the finished vault and showing a casket therein. Fig. 2 is a 25 horizontal section on line 9—9, Fig. 1, while Fig. 3 is a transverse section of the vault on line 10—10, Fig. 1.

The vault comprises five separate slabs, each made of concrete and formed in suitable molds so that when the five parts are assembled a rectangular box is obtained which has smooth flat walls interiorly and exteriorly and a rounded top. The bottom slab 2 has a flat table portion 3 bordered by a 30 depressed seat 4 of the same width substantially as the thickness of the side and end slabs 5 and 6, respectively, and the vertical wall 7 which extends upwardly from the seat 4 to the top surface of the table portion 3. The seat 4 is inclined relatively to a perpendicular line with a view of providing a continuous channel or gutter 8 upon the inside of the vault when the side and end slabs are placed upon seat 4. Mortar is placed upon seat 4 but mortar alone is insufficient to 45 make a fluid-tight joint, and I therefore form or make the gutter 8 on the inside of the joint or line of union so that a thin grouting or cement may be poured into it and a continuous unbroken seal and cemented union provided on all four sides and at each corner of the box or vault. A vault made of concrete is necessarily heavy, but if made in sections each section is easily 50 handled and the vault may be assembled in the grave. However, the room for such

work in a grave is limited and under such conditions it is quite impracticable to close or seal the joints from the outside, especially the bottom and side joints. But this difficulty is overcome by providing the gutter 8 on the inside as described.

The vertical joints at the four corners of the box or vault are also made in a special way to obtain a fluid-tight seal and 60 cemented union, together with an interlocking effect. Thus each side slab 5 has a tongue 9 at each end thereof which is flush with the inner flat surface of the slab and adapted to fit loosely in a vertical channel 65 or groove 10 formed in the inner flat face of each end slab. Each groove 10 is of greater depth than the length of the tongue 9 therein to provide a vertical space 11 within which a thin cement or grouting is poured 70 to make a perfect fluid and air-tight seal and cemented union between the side and end slabs, and each space 11 is easily reached 75 and filled from above in the same way as gutter 8.

Having the four sides and bottom of the vault assembled and cemented together, and the casket placed therein, the only remaining step to be taken to close and seal the vault entirely is to lower the cover 12 in 80 place and seal and cement the joint at the top of the side and end slabs. To effect this properly in a simple, quick and practical way, I form a right-angled seat or depression 85 14 in the upper edges and at the inside of 90 each side and end slab so that the top slab 12 may rest in this depression with a loose fit all around, and the upper edge 16 of each side and end slab slopes upwardly and outwardly while the cover 12 is rounded or provided with an inwardly and upwardly sloping surface from each side and end edge. These diverging sloping surfaces jointly 95 provide a broad shallow channel or gutter 17 extending continuously around the cover 100 parallel with the straight edges of the assembled slabs, and this gutter 17 is also filled with a thin grouting or cement which flows into and fills the vertical spaces of the joint 105 and rises to a height level with the outer edge of each side and end slab, thereby uniting the cover to the side and end slabs and hermetically sealing the vault.

Each concrete slab of the vault is preferably reinforced with metal tie rods 18, and 110 the end slabs 6 have the extremities of the tie rods 19 therein bent at an angle and pro-

jected into the narrow rib portion 20 forming the outer wall of the vertical groove 10 so that this relatively weaker portion of the slab will be materially strengthened and supported. The reinforcing rods of metal 18 extending longitudinally of the cover slab also have loops or metal handles 21 affixed thereto and these handles project through the top and afford a holding means wherewith to carry the cover or to raise or lower it.

What I claim is:

A burial vault comprising separate end, side and bottom sections adapted to be assembled and cemented together, the end and side sections having each a right angled recess along its upper inner edge and provided

with inwardly and downwardly sloping upper edges outside of said recesses and inclined thereto, and a slab forming a cover for 20 said vault having a sloping top surface at its ends and sides corresponding to the slope of the edges of the sides and ends and relatively lower than the outer edges of the said side and end slabs, and which, together with the 25 sloping edges of the side and end slabs, form a broad continuous shallow sealing gutter above the joint line between said parts.

Signed at Cleveland, in the county of 30 Cuyahoga and State of Ohio, this 18th day of February, 1919.

JOHN D. BARBER..
